UNITED STATES PATENT OFFICE.

BENJAMIN H. JONES, OF ST. LOUIS, MISSOURI, ASSIGNOR TO SMITH & DAVIS MANUFACTURING COMPANY, OF ST. LOUIS, MISSOURI, A CORPORATION OF MISSOURI.

BED-BOTTOM.

1,317,299.

Specification of Letters Patent. Patented Sept. 30, 1919.

Application filed May 5, 1919. Serial No. 294,765.

To all whom it may concern:

Be it known that I, BENJAMIN H. JONES, a citizen of the United States, residing at St. Louis, State of Missouri, have invented 5 certain new and useful Improvements in Bed-Bottoms, of which the following is a full, clear, and exact description, reference being had to the accompanying drawings, forming a part hereof.

10 The present invention is directed to improvements in bed-bottoms, and particularly to the frame to which the usual link fabric composing the spring mattress is secured. The object sought is to provide a 15 corner bracket to which the side and end rails of the frame may be quickly and conveniently secured, provision being made to secure the ends of the side bars or members of the fabric directly to the adjacent ends 20 of the end rails of the frame. A further object is to provide a frame the parts of which may be quickly assembled, one which will not suffer distortion under the load imposed on the fabric or mattress, one which 25 is simple, and one possessing further and other advantages better apparent from the following detailed description in connection with the accompanying drawings in which—

30 Figure 1 represents a plan of a bed bottom showing one form of my invention applied thereto; Fig. 2 is an end view of the frame, the rail being broken away in parts; Fig. 3 is an outer side elevation of the corner bracket showing the terminal of the side rail engaging the socket thereof; Fig. 4 is a perspective of one end of the end rail; Fig. 5 is a perspective of the corner bracket supporting the end and side rails; Fig. 6 is a 35 cross-sectional detail of the bracket on the line 6—6 of Fig. 2; Fig. 7 is an inner side elevation of the corner bracket showing the offset in the wall which supports the end rail; Fig. 8 is an inside face elevation of the 40 corner bracket or looking toward the left on Fig. 7; Fig. 9 is an elevation of the side rail broken in the middle; Fig. 10 is a cross-section on the line 10—10 of Fig. 9; Fig. 45 11 is an end view of the rail; and Fig. 12 is 50 a top plan of a modified form of corner bracket.

Referring to the drawings, and for the present to Figs. 1 to 11 inclusive, 1, 1, represent the end rails, 2, 2, the side rails, and

3 the link fabric coupled to the end rails as 55 well understood in the art. The meeting ends of the several rails are usually secured to suitable corner brackets, the construction of which is materially improved by my invention. In the main form of the present 60 embodiment of the invention the corner bracket comprises an inwardly convexed arm or riser 4 terminating at the base in a substantially elliptical socket 5 for receiving 65 the elliptical (or other form of non-circular) end 2' of the side rail 2, said riser 4 forming the inner member or arm of the corner bracket, and being connected at the bottom with a similarly inwardly convexed 70 riser 4' forming the outer member or arm, the bottom connection being effected through the cross member 4'' leading from the base of the socket 5. The upper end of the riser 4 leads from the rail-supporting wall 6 of the corner-bracket, the outer face of said wall 6 being offset inwardly from the outer face 75 of the rounded corner 7 of the bracket, and being likewise depressed below the top edge of said rounded corner for a purpose presently to appear. The offset referred to is 80 represented by the reference letter *n* and the depth of the depression of the upper edge of the wall 6 below the upper edge of the corner 7 is represented by the shoulder *t*. Formed along the inner faces of the wall 6 85 and corner wall 7 is a bead or ledge 8 to increase the surface of support for the end rail 1 carried by the corner bracket. The end rails 1 are of the usual angle-bar construction, except that in the present embodiment of my invention the horizontal leg of the bar is formed with a terminal lobe or tongue extension *a* conformable to the rounded corner or wall 7, the said horizontal leg being deposited on the upper edge 90 of the corner-bracket wall 6, the vertical leg bearing against the outer face of said wall and being of a thickness equal to the offset *n*, whereby when the end of the end rail is deposited upon the corner bracket as 95 described, the outer face of the vertical leg thereof will be flush with the outer face of the corner 7; and since the horizontal leg has a thickness equal to the depth of the shoulder *t*, the upper face of said leg will be 100 flush with the upper edge of the wall 7, the lobe *a* resting on the ledge 8 disposed on the inner face of the bracket wall as previously 105

described. The wall 6 is provided with openings *o* for receiving the screw bolts *b* by which the end rail is secured to the corner bracket. The formation of the lobe or tongue *a* results in a shoulder or offset *n'*, the offsets *n*, *n'*, coming together when the parts are assembled so that the end rails 1 are practically shouldered to the corner brackets and held against longitudinal displacement across the bed frame. The lobes *a* of the end rails completely fill the corners of the brackets (Fig. 1), said lobes being availed of to anchor the springs 10 to which the side bars 11 of the link fabric are secured. It will be seen (Figs. 1, 3, 5,) that the arms 4, 4', are convexed or arched inwardly or toward the transverse axis of the bed bottom, this inward arching taking up to better advantage the strains to which the frame is subjected under the load carried by the fabric 3.

As well understood in the art, the side rails 2 when first installed in the frame are slightly cambered, the strain imposed thereon in service causing the same to straighten out. To prevent axial turning of these rails under the straightening action is the object of the elliptical or oval terminals 2' and the sockets 5 which receive them. The non-circular cross-section of these members (2', 5,) prevents rotation of the rails so that they eventually straighten out without danger of the frame suffering any distortion or twisting, and the frame or bed bottom will always rest evenly in the well of the bed. I am aware that the use of tubular side rails elliptical or non-circular in cross-section is old, but I am not aware of cylindrical rails terminating in elliptical or non-circular formations as here shown and described. A cylindrical pipe (that is, circular in cross-section) is cheaper to construct and may be always kept in stock; and when the occasion comes to construct a rail therefrom the ends thereof may be squeezed out of round with the same ultimate results as with the use of pipes or tubes that are non-circular in cross-section.

I need not of course limit myself to a corner bracket having a rounded corner. Thus, in the modification shown in Fig. 12, I show a corner bracket 20 with a square corner 21, the rail 1' being formed with a square lobe *a'* in lieu of the rounded lobe *a* in the first form described. I may depart from the present construction in minor particulars

without affecting the nature or spirit of the invention.

Having described my invention what I claim is:

1. In a bed-bottom frame, a corner bracket provided with a riser or arm terminating at the top in a rail-supporting wall offset inwardly from the outer bounding face of the corner wall of the bracket and depressed below the upper edge in which said corner wall terminates, the corner of the bracket being formed to receive the adjacent terminal of the rail supported by the wall aforesaid, extending beyond the offset against which the main body of the rail is shouldered. 70

2. In combination with a corner bracket of a bed bottom frame provided with a riser terminating at the top in a rail-supporting wall offset inwardly from the outer face of the corner wall of the bracket and depressed below the upper edge of said corner wall, an angle rail having its horizontal leg terminating in a lobe conformable to the contour of the corner wall, said leg resting on the rail-supporting wall of the bracket, the edge of the lobe being offset from the outer face of the vertical leg a distance equal to the depth of the offset of the rail-supporting wall from the corner of the bracket, and the thickness of the horizontal leg conforming substantially to the depth of the shoulder between the upper edge of the corner and the depressed edge of the rail-supporting wall, said lobe serving as a means for anchoring the side members of the link fabric of the bed bottom thereto. 80 90

3. A bed-bottom corner bracket comprising a pair of arms connected at the bottom and spaced apart, a wall connecting the upper ends of the arms, a portion of said wall operating as a rail support and being offset inwardly from the outer face of the corner portion of the wall, and having its upper edge depressed below the corresponding edge of the corner portion, a socket at the base of the inner arm for receiving the adjacent end of a side rail, the aforesaid wall of the bracket being provided with a ledge to afford an increased bearing surface for the rail supported thereby. 100 105

In testimony whereof I affix my signature in presence of two witnesses.

BENJAMIN H. JONES.
